DESIGN FOR A HANDBAG CLASP

Casper Lowenstein, Brooklyn, N. Y., assignor to United-Carr Fastener Corporation, Cambridge,
Mass., a corporation of Massachusetts

Application February 1, 1938, Serial No. 74,771

Term of patent 3½ years

To all whom it may concern:

Be it known that I, Casper Lowenstein, a citizen of the United States and a resident of Brooklyn, in the county of Kings and State of New York, have invented a new, original, and ornamental Design for a Handbag Clasp, of which the following is a specification, reference being had to the accompanying drawing, forming a part thereof, in which

Fig. 1 is a top plan view of a handbag clasp showing my new design;

Fig. 2 is a front elevational view of the device shown in Fig. 1; and

Fig. 3 is a end elevational view of the device shown in Figs. 1 and 2.

I claim:

The ornamental design for a handbag clasp, as shown.

CASPER LOWENSTEIN.
